UNITED STATES PATENT OFFICE.

CARLTON F. MCKINNEY, OF DETROIT, MICHIGAN, ASSIGNOR TO THE REPUBLIC RUBBER COMPANY, OF YOUNGSTOWN, OHIO, A CORPORATION OF OHIO.

RUNWAY FOR WINDOWS

Application filed August 13, 1926. Serial No. 128,992.

My invention generally stated, relates to vehicle bodies, but more particularly to windows for the bodies of closed vehicles, including means for permitting and facilitating the opening and closing thereof.

It has for an object the production and use of elastic runways or channels, within which sashless glass windows are arranged and adapted to slide freely in the process 10 of opening or closing.

It has for a further object the production and use of sound-deadening runways or channels of the character indicated, with special cushioning means, and with means 15 for automatic adjustment to provide for windows of varying thickness.

For a further object this invention contemplates the production of elastic runways of the character aforesaid, capable of exerting relatively increased lateral pressure locally upon the surfaces of slideable windows, and at the same time of reducing the area of frictional contact between runways and windows, as compared with structures heretofore generally employed.

As a further object this invention contemplates and provides improved means for retarding the admission of moisture between runways and window.

With the foregoing and other objects in view the present invention will now be hereinafter particularly described and set forth by the appended claims.

In the accompanying drawings which 35 form part of this application for Letters Patent, and whereon like characters indicate corresponding parts in the several views:

Figure 1 is a horizontal sectional view taken through one window frame, my improved runway, and a fragment of a sashless glass window in operative relation;

Figure 2 is a transverse sectional view taken through the present improved runway or channel as an article of manufacture detached; and

Figure 3 is a perspective view of a portion of one runway or channel also unattached.

Reference being had to the drawings and to the numerals thereon, 4 indicates the 50 usual window or door frame of a closed vehicle such, for example, as an automobile.

Countersunk in the frame 4 is the improved runway or window channel 5, secured in place by the usual, or any approved 55 means.

This runway or channel is made of a highly elastic material such as rubber, and is of unitary construction, having a base portion 6 which upon its under surface is longitudinally serrated as shown at 7. The purpose 60 and effect of said serrations or corrugations 7, upon the under surface of base 6, is that of forming a permanent and more efficient cushion between the runway and its window frame, to prevent vibrations and chattering, 65 which might otherwise result from the relative movement of said parts, during passage of the vehicle over rough and uneven road beds, at all times and particularly after the rubber, of which these runways are preferably made, has become relatively hard with 79 age. These corrugations also serve to lighten the structure as a whole, and assist in securing it in its operative position.

Rising from the base 6 of these runways, 75 and integral therewith, are oppositely disposed co-acting side walls 8, 8, normally of converging form as shown, and each terminating at its upper edge in a continuous hollow bead 9 as best shown by Figure 2. 80

Crossing the bottom of the runway and enveloping both side walls 8, 8, thereof, is a suitable fabric covering 10, which may be made of felt, suede, velvet, velveteen, or any other flexible textile material, and which 85 preferably extends down the outer sides of the walls 8, 8, to approximately the base of the structure, and is glued or otherwise securely attached.

This being a description of the invention, 90 its use and operation are so apparent that no further and detailed description thereof would seem to be necessary.

A frameless glass window such as indicated in Figure 1 by the letter A, positioned 95 within its runways 5, is capable of sliding freely in both directions. These windows are usually of plate glass, but even in plate glass there may be some variations as to thickness. This however, is fully provided 100 for and compensated for, by the converging arrangement of side walls 8, 8, and the oppositely disposed inwardly projecting character of the hollow beads 9, 9, upon the edges of said walls, serving also to absorb 105 vibrations and to effectually cushion the window A in all directions without undue friction.

The foregoing being a description of one practical embodiment of my present inven- 110

tion, it should be understood that I do not consider myself limited to the particular form and arrangement of parts shown and described. On the contrary the substance 5 of this invention as hereinafter claimed, is capable of various modifications and changes in form and construction without in the least departing from the spirit of the invention.

Having thus described my invention, what 10 I now claim and desire to secure by Letters Patent is:

1. A flexible runway for windows having a base provided with a series of serrations upon its under surface, and also projecting 15 side walls arranged and adapted to contact with opposite surfaces of a slideable window pane.

2. A runway for windows formed of elastic material having longitudinal serrations covering its under surface, said runway also 20 having side walls arranged and adapted to contact with opposite surfaces of a slideable window pane.

3. A runway for windows formed of elastic material having longitudinal serrations 25 covering its entire under surface, said runway having side walls arranged and adapted to contact with opposite surfaces of a slideable window pane, and also having a fabric covering for its inner surface.

In testimony whereof I affix my signature.

CARLOS JAMES McKINNEY.
